UNITED STATES PATENT OFFICE.

MALCOLM GOODING NICHOLSON, OF GODERICH, CANADA.

RAILWAY-CAR DOOR.

No. 802,874.

Specification of Letters Patent.

Patented Oct. 24, 1905.

Application filed June 29, 1905. Serial No. 267,677.

To all whom it may concern:

Be it known that I, MALCOLM GOODING NICHOLSON, elevator weighing-clerk, of the town of Goderich, in the county of Huron and Province of Ontario, Canada, have invented certain new and useful Improvements in Railway-Car Doors; and I do hereby declare that the following is a full, clear, and exact description of the same.

My invention relates to improvements in the doors of railway-cars used for shipping grain or other similar commodities in bulk; and the objects of my improvements are, first, to reduce the time occupied in loading and unloading cars; second, to effect a saving of expense in the cost of the same, and, third, to prevent the possibility of loss of bulk commodities, such as wheat, in course of shipment. I attain these objects by the mechanism illustrated in the accompanying drawings, in which—

Figure 1 is an external elevation of a car door and frame. Fig. 2 is an internal elevation of door. Fig. 3 is a vertical section through the door and part of a car on line 1 2, Figs. 2 and 4. Fig. 4 is a sectional plan through lower part of door. Fig. 5 is a section through door-frame and door, showing fastening device. Fig. 6 is a vertical section of same.

Similar letters refer to similar parts throughout the several views.

The door, made of wood, metal, or other suitable material, is in two parts, the lower, *b b*, hinged or otherwise attached at *n n* to the upper part *b*, which is hung by hinges *m m* or other suitable device and in such a way that *b b* folds over *b* and the whole can be swung on the hinge *m m* up to ceiling of car and there held up by hooks, staple, or any other sufficient fastening. The joints between parts of doors are rabbeted, and the lower edge of

b b is also rabbeted out to fit over iron plate or threshold of door. In the upper door *b* is the loading-door *D*, rabbeted all round and hinged on top, so as to open inward, fastened 45 by button or catch at *x*, and is secured open by means of hooks, staples, or other ordinary device. In the lower door *b b* are the discharging-doors *e ee*, rabbeted all round, hinged on sides, as at *o o*, and opening outwardly. 50 One door *ee* has attached to it a vertical plate *h*, overlapping the joints of both doors *e* and *ee* in the mullion *f*. Attached to plate *h* are spindles *G G*, having a hollow nut threaded internally to receive the threaded pin *I* and 55 on outside of plate washer and drop-handle *k*. By turning nut *g* round, by means of the handle *k*, on the fixed pin *I* the doors are closed tightly into their rabbets. The lower part of door *b b* is held in similar manner by means of 60 the fixed bolts *i*, inserted into frame, and the nuts *g* and handles *k k* on inside of door.

What I claim as my invention, and desire to secure by Letters Patent, is—

The combination with a car having a door-opening, of a door hinged at the top of the opening and comprising an upper section and a lower section hinged thereto, said lower section having a rabbet-joint with said upper section and also with the sill of the doorway the 65 door adapted to fit closely to the inner side of the door-frame and each section having a door rabbeted all around therein, and a means for clamping the door tightly in place comprising a fixed bolt in the frame and a revolvable nut provided with a handle mounted on the door, all substantially as set forth. 70

Goderich, Ontario, June 26, 1905.
